(57) **CLAIM**

The ornamental design for an oral cleaning device, as shown and described.

DESCRIPTION

FIG. 1 is a perspective view of the oral cleaning device showing the new design;

FIG. 2 is a top elevation view of the oral cleaning device shown in FIG. 1;

FIG. 3 is a front elevation view of the oral cleaning device shown in FIG. 1;

FIG. 4 is a rear elevation view of the oral cleaning device shown in FIG. 1;

FIG. 5 is a left side elevation view of the oral cleaning device shown in FIG. 1; and,

FIG. 6 is a right side elevation view of the oral cleaning device shown in FIG. 1.

The bottom elevation view of the embodiments herein is flat and unornamented.

Broken lines shown in the drawings show environmental structure and are for illustrative purposes only and form no part of the claimed design.
